UNITED STATES PATENT OFFICE.

JOHN A. LUNDEN, OF CHICAGO, ILLINOIS, ASSIGNOR OF ONE-HALF TO ROBERT C. DANLY, OF CHICAGO, ILLINOIS.

PHONOGRAPH.

Application filed May 10, 1920. Serial No. 380,068.

To all whom it may concern:

Be it known that I, JOHN A. LUNDEN, a citizen of the United States, residing at Chicago, in the county of Cook and State of Illinois, have invented a new and useful Improvement in Phonographs, of which the following is a specification.

My invention relates to an improved phonograph construction by which the vibrations recorded on a record disc may be communicated without loss of intensity and tonal characteristics to an amplifying device of novel construction by which the characteristics are preserved and body and volume are imparted to the tone.

The amplifying device is preferably provided with a plurality of transverse partitions causing the sound waves to pass around their edges in wave like fashion towards the free or open end of the amplifying device, so that the parts of the amplifying device are brought into intimate association with and vibrated by the sound waves. More specifically my amplifying device consists of an enclosing casing of tubular or conical formation having transverse partition rings secured to its inner surface at intervals, between which discs of smaller diameter than the inner diameter of the shell or casing are mounted upon a rod or reed of resilient material, preferably wood, which rod is centrally supported by being secured to the sound receiving end of the amplifying device.

My invention will best be understood by reference to the accompanying drawings showing a preferred embodiment thereof in which—

The figure is a side elevation of a part of my device with the remaining parts in vertical sectional view, the parts being in assembled relation and ready for use.

Referring to the drawing, 10 designates the annular wall of a phonograph sound box having the usual lateral extension 11 for the attachment of the stylus mounting of the instrument.

12 designates the sound box diaphragm, secured in place by holding rings 13 of resilient material, while 14 designates the back wall of the sound box formed with a central aperture 15 communicating with the bore of a tubular elbow 16 forming a fixed part of said back wall.

17 designates a companion tubular elbow

attached to the aforesaid elbow 16 and having the axis of its tubular portion or branch 18 in parallel relation with the axis of the annular wall 10 of the sound box.

In the form of stylus mounting shown in 60 the drawing, 20 designates a strip of spring material rigidly secured at its respective ends to the sound box extension 11 aforesaid, with its central portion carrying a stud or post 21 having its free end formed 65 with a receiving socket in which the needle or stylus 22 is secured by a set screw 23 or other usual means.

24 designates an arm fixedly attached to the post 21 and extending laterally therefrom towards the center of the sound box, with its free end connected to the diaphragm 12 by a screw or other usual fastening means.

The tubular extension 18 has its axis inclined to the surface of the record 26 when supported on the turn table 27 of the machine, at substantially the angle of most effective engagement between the needle or stylus and the record. This tubular extension has a sliding fit in the tubular extension 28 extending from one end of the amplifying device. The extension 28 is in effect a part of an elbow, the other portion 29 of which has a substantially horizontal axis and is slightly conical towards its end engaging 85 the remaining portion of the amplifying device. The portion 29 engages the end of a cylindrical tubular portion 30 of the amplifying device which tubular portion ends in a disc 31 from which a second tubular portion 32 projects, said portion 32 being of larger diameter than the tubular portion 30, the axes of the portions 29, 30 and 32 being coincident. The tubular portion 32, is pivotally supported on a pivot bolt 34 ex- 90

tending through the end of a supporting bracket 36 which preferably is of cast metal, and of skeleton construction to insure rigidity, strength and stability. The bracket 36 extends downwardly and obliquely from 100 the pivot bolt 34 and at its other end a bracing web 37 supporting a post or column 38 which is drilled to receive a vertical supporting rod 39 which has its lower end rigidly supported by a base 40, which base is 105 rigidly secured to the top board 40' of the machine in any suitable manner as by screws as indicated.

The amplifying means itself, which may be of wood, fiber, composition, metal or any 110

sound responsive material is constructed as follows: A tubular portion 41 forms one end of the amplifying means and this portion is of an external dimension to slidingly fit in 5 the tubular portion 30 of the mounting means. The right hand end of the portion 41 as shown in Fig. 1 is open and has located therein cross arms 42 to support the right hand end of the rod 43. The other end of 10 the portion 41 which is somewhat longer than the tubular portion 30, is closed by a disc 44 through which the rod 43 projects and which forms a second support for the rod 43. The disc 44 constitutes a means for 15 supporting the inner end of the portion 41 and rod 43 from the second tubular portion 45 of the amplifying means, which portion 45 is of a diameter to enter the portion 32 of the mounting means and is of substantially 20 the length of the portion 32. At its right hand end the portion 45 is secured to a ring 46 which connects with the portion 41 thus forming a compartment between the portions 41 and 45 and the disc 44 and ring 46 25 and in addition the ring 46 reinforces the parts of the amplifying means to hold them in proper position. The left hand end of the tubular portion 45 has connected therewith the main casing 47 of the amplifying 30 means which may either be slightly conical as indicated or cylindrical or a combination of both conformations. A ring 48 is secured to the inner surface of the portion 47 at its right hand end and other similar rings 49, 35 and 50 are similarly secured and placed at substantially equal distances between the ring 48 and the open end of the portion 47. The rings 48, 49, and 50 have relatively large central openings of increasing diameter to 40 wards the open end of the amplifying means and through these central openings the rod 43 projects nearly to the free or open end of the amplifying means. The rod 43 carries a first disc 51 between the rings 48 and 49, of 45 smaller diameter than the inner diameter of the portion 47 but of larger diameter than the openings in the rings 48 and 49; between the rings 49 and 50 it carries a second disc 52 similar to the disc 51 and outside of the 50 ring 50 it carries a third similar disc 53.

To permit the sound waves to pass freely through the tubular portion 41 and into the right hand end of the amplifying means, a series of holes 54 is formed through the wall 55 of the tubular portion 41 between the ring 46 and the disc 44 and a second series of holes 55 is formed through the disc 44 between the portion 41 and the portion 45. As a result of the construction described, sound 60 waves projected into the portion 41 from the sound box are directed through the openings 54, then through the openings 55 and against the surface of the ring 48, around the inner edge of the ring 48 and against the disc 51 65 by which they are directed outwardly

against the surface of the portion 47 and around the edge of the disc 51 against the ring 49, around the inner edge of the ring 49 against the disc 52, outwardly against the portion 47 and around the outer edge of the disc 52 against the ring 50, around the inner edge of the ring 50 against the disc 53 by which they are directed outwardly against the portion 47 and around the outer edge of the disc 53 to the hearer. The effect of the 70 path traced is that the sound waves set all parts of the amplifying means in vibration corresponding with the vibration of the sound waves and the various discs and rings produce what may be termed reed 80 effects as a result of being free to vibrate at their edges and having relatively large surfaces and they thus serve effectively to set in motion an air column of considerable size with the result that the tone is intensified 85 and given a quality depending upon the material of which the amplifying means is constructed. By making the discs and rings and particularly the rod 43 of wood, a particularly pleasing, mellow and full tone is 90 produced.

While I have shown my invention in the particular embodiment above described, it will be understood that I do not limit myself to this exact construction as I may employ 95 equivalents known to the art at the time of the filing of this application without departing from the scope of the appended claims.

What I claim is:

1. A sound chamber for phonographs 100 comprising, an inner tubular portion for receiving the sound waves, an outer tubular portion encircling said inner portion to provide an intermediate annular chamber, an inturned imperforate web connecting one 105 end of the outer portion with said inner portion, a partition closing the remote end of said inner portion and extending to and attached to said outer portion, said partition having passages connecting with said annular chamber and said inner tubular portion having orifices adjacent to said partition.

2. A sound chamber for phonographs 115 comprising, an inner tubular portion for receiving the sound waves, an outer tubular portion encircling said inner portion to provide an intermediate annular chamber, an inturned imperforate web connecting one 120 end of the outer portion with said inner portion, a partition closing the remote end of said inner portion and extending to and attached to said outer portion, said partition having passages connecting with said annular chamber, a secondary partition arranged 125 in said outer portion in spaced relation to the aforesaid partition and provided with a central passage, the said inner tubular portion having lateral orifices intermediate its length.

130

3. A sound chamber for phonographs comprising, an inner tubular portion for receiving the sound waves, an outer tubular portion encircling said inner portion to provide an intermediate annular chamber, an inturned imperforate web connecting one end of the outer portion with said inner portion, a partition closing the remote end of said inner portion and having passages connecting with said annular chamber, said inner tubular portion having orifices communicating with said annular chamber, and said inner portion extending longitudinally beyond said outer portion to provide a neck for engagement with the outlet end of the tone arm of a phonograph. 35
- 5 10 15 20 25 30
4. A sound chamber for phonographs comprising, an inner tubular portion for receiving the sound waves, an outer tubular portion encircling said inner portion to provide an intermediate annular chamber, an inturned imperforate web connecting one end of the outer portion with said inner portion, a partition closing the remote end of said inner portion and having passages connecting with said annular chamber, a secondary partition arranged in said outer portion in spaced relation to the aforesaid partition and provided with a central passage, said inner tubular portion having ori- fices communicating with said annular chamber, and said inner portion extending longitudinally beyond said outer portion to provide a neck for engagement with the outlet end of the tone arm of a phonograph. 35
5. A sound chamber for a phonograph comprising a shell, a rod supported in said shell adjacent the admission end of said shell and extending unsupported towards the delivery end of said shell, disks carried 40 by said rod of smaller diameter than said shell, and flat rings having central clearance openings supported by said shell between said disks.
6. A sound chamber for a phonograph comprising a shell, a rod supported in said shell adjacent the admission end of said shell and extending unsupported towards the delivery end of said shell, disks carried by said rod of smaller diameter than said shell, and flat rings having central clearance openings supported by said shell between said disks, said shell being of conical conformation and said disks and rings alternating to form a wave-like path for 55 sound waves around the edges of said disks and rings.

In witness whereof, I hereunto subscribe my name this 29th day of April, A. D. 1920.
JOHN A. LUNDEN.
